UNITED STATES PATENT OFFICE.

HARRY C. ADAM, OF ST. LOUIS, MISSOURI.

ELECTRIC-LIGHTING FIXTURE.

Original application filed March 8, 1922. Serial No. 541,989. Divided and this application filed January 5, 1923. Serial No. 610,840.

To all whom it may concern:

Be it known that I, HARRY C. ADAM, a citizen of the United States, residing at St. Louis, Missouri, have invented a certain 5 new and useful Improvement in Electric-Lighting Fixtures, of which the following is a full, clear, and exact description, such as will enable others skilled in the art to which it appertains to make and use the 10 same.

This invention relates to electric lighting fixtures, and has for its object to provide a light-weight lighting fixture of simple design and inexpensive construction, 15 that is easy to install, my present application being a division of my pending application for electric lighting fixture, Serial No. 541,989, filed March 8, 1922.

Figure 1 of the drawing is a vertical sectional view of a lighting fixture constructed in accordance with my present invention; and

Figure 2 is a vertical sectional view, illustrating a slight modification of my invention.

Briefly stated, my improved lighting fixture is composed of a sustaining element that is adapted to be directly connected to a ceiling or a ceiling outlet box or suspended 20 below a ceiling by a chain or other suitable means, a canopy, an electric receptacle arranged inside of the canopy and supported by a means that is connected to said sustaining element, and a retaining means for the canopy projecting downwardly from the 25 means that supports the electric receptacle. The sustaining element of the fixture is preferably provided with a positioning portion for the canopy and the retaining means 30 for the canopy is so constructed that it will cause the canopy to be held firmly against said positioning portion.

Referring to the drawings which illustrate my invention, A designates the sustaining element of the fixture which preferably consists of a substantially disk-shaped sheet metal stamping that is adapted to be connected by screws or other suitable fastening devices 1 to a supporting structure which may consist of a ceiling or a ceiling outlet box, as shown in Figure 1, or suspended from a ceiling by a chain or the like connected to an eye bolt 1^a in said member, as shown in Figure 2. B designates 55 the canopy of the fixture which is so pro-

portioned and arranged that it will surround the sustaining element A and hide it from view, C designates an electric receptacle arranged inside of the canopy B, and D designates a member inside of the canopy 60 which supports the electric receptacle C.

The sustaining element A is provided with a canopy positioning portion formed preferably by an integral, downwardly-projecting flange 2 on its peripheral edge, and the canopy B is provided with an annular ledge or shoulder 3 that is adapted to bear against the lower edge of said flange, thereby maintaining the canopy in parallel relationship with the ceiling on which the fixture 70 is mounted and preventing the upper edge of said canopy from being forced into or imbedded in the ceiling during the operation of arranging the canopy in operative position. The member D inside of the 75 canopy which carries the electric receptacle C preferably consists of a horizontally-disposed bar which is suspended from the sustaining element A by means of screws 4, rigidly connected at their upper ends to the 80 sustaining element in any suitable manner, the screws 4 shown in Figure 1 being provided with heads that are arranged in depressions or pockets 5 in the top side of the sustaining element A and retained in position 85 in said depressions by nuts 6 on the screws that bear against the underside of the sustaining element. The supporting member D for the electric receptacle of the fixture is mounted in such a way that it can 90 be adjusted vertically so as to raise and lower said receptacle, this being effected by mounting the member D on the screws 4 and retaining it in position by means of nuts 7 on said screws arranged above and below 95 said member.

Various means may be used for clamping the shoulder 3 on the canopy against the portion 2 of the sustaining element A. In the fixture shown in Figure 1 the member D 100 is provided with depending screws 8 that project downwardly through the canopy and exposed nuts 9 are mounted on said screws on the underside of the canopy and in the fixture shown in Figure 2 the screws 105 4 that connect the member D to the sustaining element A are used for retaining the canopy in position, said screws 4 projecting downwardly through a flange on the inside of the canopy and having nuts 9^a 110

mounted on the lower ends of same underneath said flange. By tightening the nuts 9 or 9^a the canopy will be moved upwardly, thereby causing the shoulder 3 on the canopy to be clamped tightly against the canopy positioning portion 2 on the sustaining element A.

A lighting fixture of the construction above described is inexpensive to manufacture; it is light in weight, due to the fact that the sustaining element consists of a sheet metal stamping and it can be installed easily by first assembling the electric receptacle C with the sustaining element A to form a single unit that can be easily mounted on the supporting structure, and thereafter arranging the canopy in operative position over the sustaining element and securing said canopy in position by devices that project downwardly from the member D inside of the canopy which carries the electric receptacle, it being impossible to arrange the canopy in an angular position with relation to the sustaining element or force the upper edge of the canopy into the ceiling by unequal or excessive tightening of the devices that retain the canopy in operative position, due to the fact that the depending flange 2 on the sustaining element and ledge

3 on the canopy against which it bears limit the upward movement of the canopy relatively to the sustaining element.

Having thus described my invention, what I claim as new and desire to secure by Letters Patent is:

An electric lighting fixture, comprising a sustaining element consisting of a substantially disk-shaped sheet metal member provided at its peripheral edge with an integral, downwardly-projecting flange, a canopy arranged so as to completely conceal said sustaining member from view and provided with a ledge that is adapted to bear against the bottom edge of said flange, an electric receptacle arranged inside of the canopy, a supporting bar for said receptacle, screws fastened at their upper ends to said sustaining member and projecting downwardly through said supporting bar, nuts on said screws that are adapted to be adjusted so as to raise or lower said supporting bar, and means for forcing the canopy upwardly against the flange on said sustaining member consisting of devices projecting upwardly through the canopy and screwed into said supporting bar.

HARRY C. ADAM.
